(57) **CLAIM**

The ornamental design for a handle of a conducted electrical weapon, as shown and described.

DESCRIPTION

FIG. 1 is a top, front, left perspective view of a handle of a conducted electrical weapon showing our new design;

FIG. 2 is a bottom, rear, left perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines immediately adjacent to the shaded area define the bounds of the claimed design and form no part thereof. The broken lines depicting the remainder of a handle of a conducted electrical weapon show features that form no part of the claimed design.
